UNITED STATES PATENT OFFICE.

FRANK E. DAVIS, OF SOMERVILLE, MASSACHUSETTS.

FARE-REGISTER.

SPECIFICATION forming part of Letters Patent No. 248,717, dated October 25, 1881.

Application filed September 27, 1880. (No model.)

To all whom it may concern:

Be it known that I, FRANK E. DAVIS, of Somerville, in the county of Middlesex and State of Massachusetts, have invented a new 5 and useful Numerical Register, of which the following is a specification.

My invention relates to that class of registers that are used to give the sum of units of actions, the action being caused by the movement of a knob or lever which is actuated either directly or indirectly by the user; and it consists in combining, with a series of indicating-disks, a series of ratchet-wheels and a single pawl, the end of the pawl being provided with projections of unequal length, one projection working on one wheel only, each wheel having one notch so deep that it will allow that projection of the pawl which operates it to penetrate so far as to cause the projection that is intended to operate on the next disk to work. Thus the two disks will move together. This same construction being applied to all of the ratchets in the series, it will be understood that a certain number of movements of the 25 pawl will cause all of the disks to move and to register to the full extent of the device.

In the drawings, Figure 1 is an interior view in side elevation. Fig. 2 is a front elevation, a part being represented as broken out for the 30 purpose of showing the interior construction. Fig. 3 is a perspective view of the pawl. Figs. 4, 5, and 6 are drawings to represent the ratchet-wheels which operate indicating-disks.

Let A represent the outside casing of my 35 enumerator, and B the actuating-knob.

B' is a sliding bar, which is forced outwardly by the action of the spring B², one end of the spring B² resting against a fixed buttress, C, attached to the case A, while the other end 40 acts against a pin, b, in the sliding bar B'. In use the operator pushes the bar B' in, and the spring B² throws it out when released. Thus a back-and-forth motion is given to the bar B'.

D is a pawl attached to the sliding bar B'. 45 This pawl D has a spring, D', which forces it inwardly toward the ratchet-wheels, one of which, H, is indicated by dotted lines in Fig. 1, the other two being partially shown at H' H², Figs. 1 and 2, the same being shown in full 50 in Figs. 4, 5, and 6, all of these ratchet-wheels being mounted on the same shaft L, each ratchet-wheel having attached to it an indicat-

ing-disk, the ratchet H² being attached to the unit-indicating disk K², the ratchet H' being attached to the tens-indicating disk K', and the 55 ratchet H being attached to the hundreds-indicating disk K.

E is a spring-pawl divided into three parts, one part resting upon each ratchet and holding it in place. The pawl D has three projections, 60 d d' d², which act respectively upon the ratchets H H' H².

The operation is as follows: The longest projection d² acting upon the unit-ratchet H², and being longer than the other two projections, 65 it prevents them from engaging with the teeth of the ratchets H' H, except when the deep notch M² on the ratchet H² comes into place. Then the projection d² falls into the deep notch and allows the projection d' to act on the tens-ratchet H'. Thus the tens-ratchet will be, 70 turned one notch or one-tenth of its circumference as often as the unit-ratchet H² has made a whole revolution. When the tens-wheel has made a full revolution, then the notches M' 75 and M² will coincide, so as to allow both of the projections d' d² to enter the deep notches, thus causing the short projection d to engage with the hundreds wheel H and cause it to move one 80 notch.

By this device I am enabled to record units, tens, and hundreds without the intervention of any train of wheels or levers. The capacity of the enumerator might be increased indefinitely by adding to the number of the indicating-disks. 85

For convenience in reading the figures I have an opening at A², Figs. 1 and 2. This may be protected by glass or mica, if desirable.

To set the indicating-disks K K' K², I have 90 a part, A', of the case A hung on a hinge, a, so that it can be turned back and allow the user to adjust the disk to the zero-points.

I claim—

The combination, in a registering device, 95 of the knob B, its sliding bar B', spring B², pawl D, having projections d d' d², with the ratchet-wheels H H' H², and disks K K' K², all operating together substantially as described, and for the purpose set forth.

FRANK E. DAVIS.
